UNITED STATES PATENT OFFICE.

GEORGE HANDLEY, OF PALMERS GREEN, ENGLAND, ASSIGNOR TO PERCY WILLIAM BULLOCK, OF LONDON, ENGLAND.

ROTARY PUMP FOR PUMPING LIQUIDS.

1,353,745.

Specification of Letters Patent. Patented Sept. 21, 1920.

Application filed October 24, 1919. Serial No. 333,022.

To all whom it may concern:

Be it known that I, GEORGE HANDLEY, a subject of the King of Great Britain, residing at Palmers Green, in the county of Middlesex, England, have invented new and useful Improvements in Rotary Pumps for Pumping Liquids, of which the following is a specification.

This invention relates to pumps of the type in which a cylindrical rotor is caused to move within a cylindrical chamber of larger diameter, by means of an eccentric mounted on the driving shaft, the rotor having attached to, or formed upon it, a blade or stem, dividing the pump chamber into two compartments, such stem being provided with a channel leading to the pump outlet, and sliding in an oscillatory bearing.

The object of the present invention is to provide a rotary pump of the type specified so constructed as to conserve the momentum of the incoming fluid in order that such momentum may be fully utilized in insuring that the fluid shall follow the rotor and so enable the maximum effective speed of running to be attained.

This object is attained in a single pump by means of an annular chamber surrounding the pump chamber and in a twin pump in which a pair of pumps are driven from a single shaft, by directing the fluid into each pump alternately by means of a special distance piece.

In the case of a single pump, an annular chamber is provided to surround almost completely the pump chamber proper. One end of said annular chamber communicates with the pump chamber at a point adjacent to one side of the oscillatory bearing, and the other end terminates near the other side of the oscillatory bearing, where it forms a blind end. A flanged opening at the bottom of the annular chamber forms the point of communication with the suction pipe.

In the case of a twin pump the need for an annular chamber to control the fluctuations of the flow is not so great, but there is still considerable advantage in having a large body of liquid quite close to the inlets of the pumps. For this purpose the twin

pumps are mounted on opposite sides of a distance piece which is hollow and takes the place of the annular chamber. The part of the driving shaft which passes through the distance piece is supported by a bearing which in turn is surrounded by an annular chamber having a flanged opening at its lower part for attachment to the suction pipe. At the upper part of the annular chamber a passage leads to the inlets of the pumps, which in this case open sidewise. The side plates of the distance piece which support the bearing and the annular chamber also carry a common outlet chamber into which the pumps discharge and to which the common outlet pipe is attached.

This construction of pump moreover lends itself very conveniently to the fitting of a strainer in the liquid thoroughfare in such a manner as to permit of easy removal for cleaning purposes without disturbing the line attachments.

My improved arrangement insures simplicity and ease of construction, mounting and fitting, with reduction of overall dimensions of pump and pipe line attachments; it serves to obtain a direct pipe line in the vertical plane of the pump spindle so that the pump can be mounted directly, over a well or mine shaft for example; and it also insures a more uniform distribution of external and internal stresses and thus renders a lighter construction possible.

Moreover as applied to a twin pump it insures a continuous and uniform flow both in the suction and in the delivery pipe but particularly in the former as this governs the output of the pump at any given speed, in revolutions per minute, and also the maximum effective speed of running.

The arrangement further insures a higher maximum, effective, speed and consequent output than is possible with a single pump of the same total displacement; it facilitates stream line construction of passages and gradual increase of fluid velocity in approaching the pump chamber, inlet openings; it enables fluid to be supplied to each pump alternately in the most direct manner possible; it reduces losses due to unavoidable

able change of direction, to a minimum; and it conserves the velocity given to a fluid on discharge from the pump chamber by a stream line form of confluence to the common outlet.

In the accompanying drawings which illustrate my invention:—

Figure 1 is a half side elevation and half section of a single pump.

10 Fig. 2 is a half elevation and half section taken on the line $x-x$, Fig. 1.

Fig. 3 is a half horizontal section and half plan of the pump.

15 Fig. 4 is a half side elevation and half section through one of the cylinders of a twin pump.

Fig. 5 is a half elevation and half section taken on the line $y-y$, Fig. 4.

20 Fig. 6 is a section taken on the line $z-b$, Fig. 5.

Fig. 7 is a transverse section through one cylinder of a twin pump provided with a strainer, and

25 Fig. 8 is a section taken on the line 8 8 of Fig. 7.

Like letters of reference denote corresponding parts in the several figures.

Referring to Figs. 1 to 3 A is the pump body, B the rotor, C the driving eccentric, 30 D the driving shaft, E the stem of the rotor, F the oscillatory bearing through which the stem E slides, and G the pump chamber.

Between the pump body and the pump chamber is an annular chamber H almost 35 completely surrounding the pump chamber. This annular chamber communicates at one end with the pump chamber through an opening J adjacent to the oscillatory member which is channeled at K as shown. The 40 other end of the annular chamber terminates at L in a dead end near the other side of the oscillatory bearing. A flanged opening at M forms the communication with the suction pipe. The outlet from the pump chamber is through a channel N in the stem of the rotor leading to a flanged opening O.

45 The operation of the pump is as follows:—

During the first portion of the cycle of operations, the suction is increasing and the 50 pump draws upon the body of liquid nearest to the inlet, namely, that in the annular chamber. The residual air left in the upper part of the blind end of the annular chamber serves as a spring and by expanding 55 allows the liquid on this side to descend, partly taking the place of that first drawn upon and preventing undue acceleration of the stream in the suction pipe. During the second part of the cycle, suction diminishes 60 to zero and the stream of liquid from the suction pipe instead of being checked, flows into the blind end of the annular chamber, the residual air at this end contracting after its previous expansion, and allowing the 65 liquid to take its place. Thus the liquid in

the annular chamber has a regular oscillatory motion while the flow in the suction pipe is steady.

Referring now to Figs. 4 to 6, the twin pumps P, P are mounted on opposite sides 70 of a hollow distance piece Q which takes the place of the annular chamber.

The driving shaft D passes through both pumps and the distance piece; the eccentricities of the two pumps are set at an angle of 180° 75 with respect to each other so that the suction of one pump coincides with the discharge from the other pump, and thus tends to make the discharge fairly uniform. The part of the driving shaft D which passes 80 through the distance piece is supported by a bearing R which in turn is surrounded by an annular chamber S having a flanged inlet opening T at its lower part, and at its upper part a passage U leading to the pump inlets V on each side thereof. O is a common outlet for both pumps which outlet 85 communicates with the discharge side of each pump through openings W.

The above described constructions of 90 pumps allow a high velocity of flow to be attained on account of the flow in the suction pipe being substantially uniform.

In the modification illustrated in Figs. 7 and 8 a strainer is inserted in the pump inlets to intercept dirt and prevent same from 95 entering the pump chambers. The vestibule V leading to the pump chambers is of approximately semi-cylindrical form. Its open side leads directly to the pump chamber and its end walls are pierced by two circular openings 11, 12. The inner opening 12 faces a corresponding opening 13 in the distance piece and constitutes the inlet; the opening 11 is closed by a removable cap 100 14 in the cover plate.

The strainer 15 consists of a cylinder of wire gauze or perforated metal, open at 105 each end. The ends of the strainer fit the circular openings 11, 12 so that fluid drawn from the distance piece must first enter the strainer at its inner end and pass through the strainer into the pump chamber.

The removable cap 14 enables the strainer to be taken out for cleaning purposes without disturbing any other part of the pump. If desired the removable cap 14 can be fitted with a circular glass window so that the condition of the strainer can be seen from the outside at any time.

120 What I claim is:—

1. A pump of the pendulum rotary type, comprising a pump body having a pump chamber formed therein, a rotor mounted in said chamber, a stem on said rotor, an oscillatory bearing through which the said stem slides, an annular chamber surrounding almost completely the pump chamber and communicating at one side with the pump chamber at a point adjacent to the os- 125 130

cillatory bearing, the other side of the annular chamber terminating in a blind end near the oscillatory bearing, and an inlet for liquid at an intermediate point of the 5 annular chamber whereby the momentum of the incoming liquid may be fully utilized in insuring that the liquid shall follow the rotor and enable the maximum effective speed of running to be obtained.

10 2. A twin pump comprising two pumps of the pendulum rotary type, a hollow distance piece on opposite sides of which the two pumps are mounted, the interior of the hollow distance piece communicating with 15 the suction inlet, and with the inlets leading to the pump chambers.

3. A twin pump comprising a hollow distance piece, a suction pipe communicating with the interior of the hollow distance 20 piece, a pump of the pendulum rotary type mounted on each side of the distance piece and provided with passages forming communications between the pump chambers and the interior of the distance piece, and a 25 common outlet pipe formed on the distance piece in line with the suction pipe and communicating with the outlets from the pump chambers.

4. A twin pump comprising a hollow distance piece, a suction pipe communicating 30 with the interior of said distance piece, a pump of the pendulum rotary type mount-

ed on each side of the distance piece and provided with passages forming communications between the pump chambers and 35 the interior of the distance piece, said pumps being so set that one is discharging while the other is drawing in, and a common outlet pipe formed on the distance piece and communicating with the outlets from the 40 pump chambers.

5. A twin pump comprising two pumps of the pendulum rotary type, a hollow distance piece on opposite sides of which the two pumps are mounted, the interior of the 45 hollow distance piece communicating with the suction inlet, and with the inlets leading to the pump chambers and a strainer arranged in the inlet passage leading to each 50 pump chamber.

6. A twin pump comprising two pumps of the pendulum rotary type, a hollow distance piece on opposite sides of which the two pumps are mounted, the interior of the hollow distance piece communicating with 55 the suction inlet, and with the inlets leading to the pump chambers, and a strainer arranged in the inlet passage leading to each pump chamber and withdrawable through openings in the pump body.

GEORGE HANDLEY.
